CLOTH-SPREADING MACHINE

Theodore J. Gundlach, Belleville, Ill.

Application July 18, 1942, Serial No. 451,510

12 Claims.

(Cl. 270—31)

This invention relates to improvements in cloth-spreading machines, and more particularly to improved devices for singling and spreading doubled fabrics from a supply bolt or roll thereof.

For some time past devices have been employed for the general purpose of transferring and spreading bolted or rolled cloth or fabrics, for example, onto a horizontal cutting surface such as a table. There are prevalently in use several types of such devices involving a rolling carriage, arranged to traverse an elongate cutting table, and in so moving, serving to unroll as from a horizontal supply bolt, the cloth as paid out from such bolts, and to deposit the cloth in superposed layers upon the table, whereon it is adapted to be cut for the manufacture of garments or the like. The present invention relates to devices of this general and broad category, namely, those which operate back and forth over an elongate work table. However, the present improvements have been particularly evolved to meet the demand for a successful and unfailingly dependable machine which will pay out and spread in evenly registered, superposed layers, without wrinkles or unwanted folds, single layers of cloth or fabric from a supply roll or bolt in which the fabric is initially doubled. It may be noted that this requirement creates a problem considerably different from that of unrolling a single fabric from a supply roll on which the fabric is wound in single layers. It is accordingly a general object of the present invention to provide a device of the type briefly referred to for the general purpose of singling and spreading a doubled fabric and depositing same on a horizontal surface in single layers which are in exact registration, free of wrinkles and under a slight, although uniform, tension at the time of deposit.

Another object of the invention is attained in the provision of an improved agency for parting, spreading and laying out in single thicknesses, initially doubled thicknesses of cloth, all in a manner to deposit the cloth without wrinkles and in an optimum condition for cutting or other processing.

A further object of the invention is attained in an improved combination of supply reel for bolted fabrics, with singling and spreading means for unfolding the doubled fabric, in a manner conducting to uniformity of spreading operation and simplicity of structure.

Yet another object of the invention is attained in a combination with and an improved arrangement of cloth supply reel, cloth singling element, and flattening and tensioning elements by which

the cloth is constrained to an exact position of deposit on a work table or the like, as for cutting.

Yet another object of the invention is attained in improved and simplified means for more quickly than with prevalent machines, effecting an adjustment of cloth spreading apparatus to accommodate it to the disposition of single layers of cloth of different widths.

Another object is attained in an improved arrangement for periodically lifting the cloth spreading and tensioning agencies in response to increasing height of the deposited cloth, due to the increasing number of superposed layers thereof as the device is operated.

15 Numerous other objects of the invention are attained in the provision of certain advantageous self-adjusting features whereby as certain primary adjustments are made to accommodate different widths of cloth, other adaptations to 20 such different widths are automatically effected.

The foregoing and numerous other objects will more clearly appear from the following detailed description of a presently preferred embodiment of the invention, all as will best be understood 25 in connection with the accompanying drawings, in which:

Fig. 1 is a top or plan view of a cloth spreading carriage embodying present improvements, and a fragmentary portion of a cutting table along 30 which the carriage operates; Fig. 2 is a side elevation of the carriage and a portion of the table; Fig. 3 is a front elevation of the carriage, showing in dotted lines an adjusted relation of certain of its parts to accommodate different widths of 35 cloth; Fig. 4 is a section in a vertical plane, of a portion of the supply bolt reel as taken along line 4—4 of Fig. 1; Fig. 5 is a view taken in a vertical plane, being a fragmentary sectional elevation as viewed along line 5—5 of Fig. 3, in order better 40 to show the relation of certain of the final cloth-spreading and tensioning rollers, and Fig. 6 is a vertical section taken at a right angle to the view of Fig. 5, particularly along the line 6—6 of Fig. 5.

Referring now by characters of reference to 45 the drawings, the assembly, by preference and as shown, is adapted for the spreading or laying of successive, single, superposed layers of cloth on a horizontal surface, whereby multiple layers of such cloth may be processed, as by cutting. A work table of this order, indicated generally by the letter T, will be understood to be elongate in nature, being often made in lengths of 80 to 100 feet. Extending parallel to and along one lateral margin of table T is a single track structure TR secured to the table by spacers S and

screws SC. It may be noted that, since the width of the carriage, later to be described, may be varied to accommodate different widths of single layers of cloth, it is desirable that only one rail of track be employed.

The device of the present invention is preferably mounted on a vehicle or carriage indicated generally at 10, which, as will be understood, operates lengthwise of the table and is constrained to a definite linear path of movement thereover, through the provision of a pair of wheels 11 each provided with a track groove 12 operating on the track TR. At the opposite side of the carriage a pair of wheels 13, with wide, cushioned treads, operate directly over the table top and, as will appear, along a line which may vary according to the width adjustment of the carriage. Suitable axle elements 14, and journalled bearing arms or axle supports 15 coact with the wheels in supporting side members 16 and 17 of the frame of the carriage. A generally rectangular frame or chassis of the carriage proper is completed as by end channel elements 20 and 21. Although the carriage is adapted to operate in either direction, for convenience of future description the end of the carriage identified with cross member 21 will be referred to as the front, and the opposite end defined by cross frame member 20 may be considered the rear of the carriage. The rectangular aspect of the carriage frame is preserved and the frame suitably reinforced in any of numerous ways which will readily suggest themselves, but in the present example corner brace members 22 serve this purpose. These may be welded, bolted or otherwise secured to the end and side elements of the frame.

The desirability for effecting an occasional width adjustment of the carriage is met by forming each of the rear and front end members of the frame such as 20 and 21, of two slidably related parts, with one of such parts being so dimensioned that it will operate within and along the other. This objective is conveniently realized by selecting two channel members, one of which will slidably fit within the other, and the provision of one thereof with bolts 23 and cooperating wing nuts 24, the bolts being carried, for example, by the inner of the telescopingly related members, while the outer is provided with a suitable slot 25 for each of the bolts, whereby to permit a requisite degree of adjustment.

In order to support a reel for a supply bolt of doubled fabric, there is attached to the outermost face of the outer one of the telescoping elements 20, a generally cylindrical foot bearing or support 26 (Figs. 2 and 4). This serves as a holder and bearing retainer for a cloth reel and reel shaft, as will be hereinafter more particularly described. The letter B indicates a roll or bolt of cloth constituting a supply of the fabric to be spread; each layer, consisting of a doubled thickness or fold of the cloth, is paid out from the roll or bolt B and thence over a wishbone-like element generally indicated at 27. The general location and arrangement of the wishbone are features of importance to the successful operation of the device, as will better appear. As shown in the present example, this structure is preferably formed of a single piece of steel rod stock and hence is of curved exterior surface and aspect. The general shaping of the rod stock, resulting in the singling and dividing element 27, will best appear from Fig. 3 as including a pair of upwardly extending arms 30 and 31, these arms merging or joining each other in an apex por-

tion 32. It will be noted, however, that this peak or apex of the wishbone 27 is not sharp, but is distinctly rounded into the arms 30 and 31. At the lower extremities of the arms 30 and 31 the wishbone 27 is characterized by a pair of vertical supporting portions 33, and there is welded or otherwise secured to each of the opposite side members of the carriage a socket element 34. The internal bore of each socket 34 is such as firmly to support the depending ends 33 of the wishbone, and yet, when desired, to enable the wishbone 27 to be lifted readily from the sockets for detachment of the wishbone 27 from the carriage.

It is a further preference in the formation of the wishbone or singling element, that the rounded surface thereof be distinctly smooth, in fact it may with advantage be polished, or if desired, chrome-plated or otherwise treated so as to create a surface thereon which will obviate any possibility of any protuberances or rough portions snagging the fabric or cloth as same is moved thereover.

After protracted experimentation it has also been determined as highly advisable so to locate the supply reel that the bolt B pays out the cloth in a zone which is not substantially laterally offset from the rounded peak or apex 32 of the wishbone. It will best appear from the plan of Fig. 1 that a fold line indicated by the numeral 35, substantially intersects the peak 32 as the cloth progresses away from the reel. There will of course be some variation in this relation between line 35 and portion 32 because of differences in condition prevailing when a full bolt of cloth occupies the reel, and when a nearly exhausted supply bolt B is yet feeding out the cloth.

A further preference in shaping and relation of the wishbone 27 best appears from the side view of Fig. 2 wherein it is seen that the element 27 is inclined slightly from the vertical and toward the supply bolt B. This is shown as being at an angle to the vertical of about ten degrees, although some variation in this sloping is permissible with good results.

Although the specific agencies employed for finally tensioning the singled layers of cloth and constraining same to assume a distinctly horizontal position on the cutting table, are susceptible of some variation, a serviceable and practical assembly thereof is indicated by an assembly of four rollers for this purpose. Two of these constitute an upper set and are indicated at 36 and 37, while a lower pair or set consist of rollers 40 and 41. Of these, the rollers 36 and 37 are shown as supported at a constant height above the table through a pair of arms 42 constituting extensions of the side members 16 and 17 of the carriage frame and secured thereto in any suitable manner, as by bolts, certain of which are indicated at 43. The ends of the rollers 36 and 37 may be provided with threaded studs or the like 44 through which they are rotatably journalled in the extension arms 42. It will have appeared that each of the rollers 36 and 37, which is also true of rollers 40 and 41, consists of two telescoping parts, namely, a hollow element and a solid element arranged in telescoping relation. The solid portion of each of these rollers extends substantially into the hollow companion portion, thus maintaining the rectilinear aspect of the roll and the correct relation between the companion rolls of each set, irrespective of the adjusted lengths of rollers due to differing widths of the carriage 10. In this manner, incident to in-

crease in spacing of the side elements 16 and 17 of the carriage, the effective length of the rolls 36, 37, 40 and 41 is automatically cared for without separate adjusting operations.

As heretofore indicated, it is desirable to arrange for locating the lower set of rolls 40 and 41, constituting the final cloth spreading and tensioning agency, at various heights above the table T, as successive layers of cloth are deposited thereon. This is cared for by a pair of roller-supporting arms 45, one on each side of and paralleling the side frame members of the carriage. Each arm 45 is pivoted as at 46 to one of the bearing arms 15, the upper and lower adjusted positions of each arm 45 being shown respectively in dotted and solid lines by Fig. 2. Mounted at the end of each of arms 45 is a plate element 47 provided with horizontally spaced apertures (not shown) serving to receive a pair of the cap screws 44 or similar elements by which the rolls 40 and 41 are journalled. Each plate 47 is pivotally connected as by a bolt 50 (Fig. 5) to an upright guide arm 51, the guide arm in turn being free to slide vertically through a cylindrically bored guide member 52 secured to the extension arm 42, there being one of these assemblies on each side of the carriage, as will appear. From the foregoing it will have appeared that, in spite of the slight arcuate movement of the free end of the arms 45, nevertheless the rolls 40 and 41 of the lower set, as they are lifted or lowered, are constrained to movement in substantially vertical planes, the guide 52 and guide rod 51 serving somewhat after the manner of a cross-head in constraining these rolls to predetermined adjusted positions.

As a means for readily manually raising or lowering the arms 45 and hence the lower pair or set of spreading rollers 40 and 41, there is provided at each side of the carriage and supported by the extension arms 42, a cable and a ratchet winding mechanism which serves this adjustment. This assembly includes a small flexible steel cable 55 connected to each arm 45, this cable being wound over a cylindrical reel or windlass 56, peripherally provided near its inner face with a series of ratchet teeth 57 coacting with a pivoted stop pawl 58. Each reel is mounted on a shaft 60—61, the shaft 60—61 consisting of telescopically related parts, one of which such as 61, is of solid square section while the parts 60 may be tubular with a hollow internally squared end so as telescopically to receive the solid end 60. Manual means for lifting or lowering, through the cable assembly, the arms 45 and rollers 40—41, are shown as consisting of a pair of knurled knobs 62 and 63, one on each side of the carriage.

It will have appeared from the foregoing description that as the shaft 60—61 is rotated clockwise (Fig. 2) the ratchet elements 57 are so arranged that rotation of the reel over one ratchet tooth, results in an appropriate lift of rollers 40—41 to account for the deposit of a single layer of cloth on the table. Thus at each pass of the machine or carriage over the table, a single notching movement of the windlass assemblies may be made at each end of the table.

It will have appeared from the foregoing that the device includes ample adjustment means, first, for varying the width of the carriage through manipulation of the various wing nuts 24 and extension of the front and rear frame members of the carriage followed by threading up of the wing nuts on the bolts 23, all in coaction with the several slots 25. The arrangement is

such as to maintain the side members 16 and 17 of the carriage in parallelism and similarly the front and rear frame members 20 and 21. As has been briefly referred to, the adjustment features include self-adjusting provisions due to the telescoping arrangement of the halves of each of rollers 36 and 37 of the upper set and 40 and 41 of the lower set. It should similarly be observed that the rod stock of which the wishbone singling element is composed, is such that it possesses inherent resilience and flexibility to a degree that, irrespective of any carriage width adjustment within usual limits, the wishbone 27 will automatically be spread or narrowed incident to the adjustment of the carriage width, all without materially disturbing the described relation between the location of the peak 32 of member 27 and the supply bolt.

Proceeding now to a more detailed description of the reel for the cloth supply bolt or roll, this includes by preference, a horizontal table conveniently formed of a relatively heavy gauge sheet metal, the table being circular in outline and indicated at 65. If desired this may, as shown, consist of a double thickness of metal, both for rigidity and as will be described, to facilitate removal and reapplication of the roll of cloth. Projecting upwardly of the rotatable table or platform 65 is a substantially flat bolt core 66, the median line of which preferably coincides with the axis of rotation of the table 65. The core 66 is so shaped as to be readily extended through the rectangular space often provided centrally of a supply bolt or roll of doubled cloth B.

A journal support for the supply bolt reel is identified in part with the sturdy cylindrical socket 26 heretofore generally described, and with which is operatively associated a stub shaft 67. The reel is thrust-journalled through an inner race 70 and an outer race 71 of a tapered roller bearing assembly mounted in a journal socket 72 in the member 26. Below the thrust bearing assembly described, a plain sleeve bearing 73 is located, principally for alignment purposes so as to preserve the perpendicularity of the axis of the reel, most of the wear incident to reel rotation being taken by the thrust roller assembly referred to. The bolt core 66 described is formed as a separate structure and may be mounted through the provision of a pair of angle elements 74 welded to member 66 and secured as by screws 75 to the table 65.

In the operation of the carriage it will be understood that there is a tendency at times, particularly as the carriage is decelerated near the ends of the table, due to the high inertia of the bolt and reel, for the reel to overrun, i. e. to unwind the cloth to a greater extent than corresponds to the linear movement of the carriage. This effect is overcome in the present structure by the provision of a small screw brake or drag, consisting of a friction disc 76 operating against the under surface of the table 65 to constitute a slight drag thereon sufficient to prevent overrunning. The disc 76 is supported at the end of a screw 77, which may be manually operated for varying the braking effect, by the screw threaded relation of member 77 to an internally threaded socket member 78.

While the operation of the improved cloth spreading machine is thought to have been apparent from the foregoing detailed description of its parts and functions of its sub-assemblies, it may be noted for completeness that the carriage 10 is first disposed on the table T, with its grooved

wheels 11 and 12 on and guidedly engaged by the single rail track TR. Assuming any adjustment in width of carriage 10 to be necessary, this fact is determined by accurately determining the length of the spreading and tensioning rollers 36, 37, 40 and 41, such measurements being taken between inner faces of a pair of set collars 80 and 81 on each of the rollers of the upper set, and similar collars 82 and 83 on the rollers of the lower set. It will have become apparent that, in operation, these collars are set along the rollers in such manner that the inner faces of the rollers are just in engagement with lateral margins of the single layer of fabric, whereby the collars tend to direct the cloth to a straight line course of deposit. As before noted, the width of the carriage is appropriately adjusted through bolts 23, nuts 24 and slots 25 to accommodate the carriage and hence the rollers proper as well as the wishbone 27 to the predetermined width of the single layer of cloth.

The width adjustments having been completed throughout, a roll or bolt B of the doubled fabric to be spread, is applied to the table 65 of the reel. For this purpose either the whole table assembly 65, 67, etc. may be lifted from its bearings and the core 66 inserted centrally of the bolt of cloth; alternately the element 65 may be made removable from a deck portion 65A therebelow, by the provision of unthreaded sockets in member 65A which receive the lower ends of screws 75. This latter arrangement is preferred as it reduces the height to which the full bolt or roll must be lifted prior to its location on the carriage.

With the supply bolt B in place, a few turns of the doubled cloth are paid out by hand, and draped over the wishbone 27 in a manner which will be apparent from Fig. 2. It will now appear that the fold 35 of the doubled fabric overrides and engages the rounded apex portion 32 of the wishbone singling element 27, in such manner that the cloth therebeyond (or to the left in Fig. 2 of the wishbone) assumes an inverted V form. From this zone the cloth is manually fed for starting, first under roller 36, thence between rollers 35 and 37, thence over roller 31, thence downwardly between rollers 40 and 41 whence the starting margin of the singled layer of fabric is deposited on the table. The starting operation will of course take place at one end of the cutting table or other surface traversed by the carriage.

It may here be noted that, as is known in the art, means (not shown) are provided for anchoring not only the starting end of the fabric laid upon the table but also for anchoring the successive end folds of the cloth thus deposited incident to the back-and-forth movement of the carriage. Since such means form no part of the present improvements it may be noted for completeness that any of several well known devices for this purpose may be utilized. A suitable device for example, is shown by Patent No. 883,687, Bendien, although any other suitable cloth-catching device for cloth-piling machines may be utilized. After catching the starting end of the cloth to be piled, the carriage 10 is moved lengthwise in successive and alternately reversed passes over the table T and track rail TR, in the present example, by manual actuation through the paired handles 85 provided for this purpose. It is of course within the intended scope of the invention to utilize power-actuating means for the carriage if and when desired, such driving means 78

being omitted in the interest of brevity of present description.

Although the action on the cloth to be deposited will now have become obvious from the drawings and earlier description, it may be noted that the effect of linear movement of the carriage is to withdraw the doubled fabric from the supply roll B, thence to move the carriage to bring the wishbone with its apex under the bight or fold 10 of the cloth, thence to drape the two previously folded layers of each turn of cloth, one over each of the arms 30 and 31 of the wishbone. In this manner the effective divergence of arms 30 and 31 produces the same effect on the folds of cloth. 15 The substantially ninety degree angularity of the cloth folds in passing over the wishbone is, between the wishbone and upper rolls 36 and 37, further enlarged so as to bring the paired folds of cloth to a 180 degree, or flattened, single-layer relation. The passage of cloth under roll 36 and over roll 37 has the effect of ironing out the fold or crease theretofore existing in the bight portion 35 of the cloth, and the slight tensioning effect imparted by rolls 36, 37, 40 and 41 serves 20 to lay the cloth as the carriage is moved, in absolutely flat formation free of wrinkles and bulges or the like, and with the successive layers in the pile of deposited cloth, all in exact superposition. Now obviously, the carriage is caused to traverse 25 the length of the cutting table T as many times as there are desired successive layers of cloth for cutting or other processing.

It will have appeared from the foregoing description that the machine as described by selected example, serves fully to attain each of the objects hereinabove expressly set forth, as well as to attain other advantages in part implied from the description of a selected embodiment.

The detail of description of the single example selected is to be understood in an instructive and not in any limiting sense, since it is obviously possible to make many changes in the assembly, sub-assemblies and arrangements of parts described, without departing from the full intended spirit of the claims hereunto appended.

45 I claim:

1. In a device for singling and spreading doubled fabrics from a supply bolt thereof, a carriage movable along a surface on which the fabric is to be deposited in single layers, a reel for the supply bolt mounted for rotation about a substantially vertical axis on the carriage, and a dividing or singling structure mounted on the carriage between the reel and zone of cloth deposit, said structure being substantially in wishbone shape formed of metal rod stock, and characterized by a smooth and rounded surface for engagement by the cloth as same is moved thereover, the singling structure being further characterized by angularly related, upwardly converging rectilinear side elements, collectively transversely bridging opposite side members of the carriage.

2. In a cloth-spreading carriage adapted to contact with a table or like surface for the deposit of single layers of an initially double-bolted fabric, a vertically disposed rotatable supply reel on the carriage, a wishbone type singler mounted in a generally transverse position on the carriage and with its apex portion in the region of the supply bolt, means enabling an adjustment in width of the frame structure of the carriage by effecting different spacings of the carriage side members, the wishbone structure being so formed 50 as to accommodate itself to different widths of

carriage while substantially maintaining the position of its apex portion with respect to the supply bolt.

3. The combination and arrangement of elements substantially as recited in claim 2, and further characterized in that the wishbone structure is disposed in a generally vertical plane substantially transversely of the carriage, but is inclined slightly toward the bolt reel on the carriage.

4. A substantially V-shaped inverted cloth singling and spreading element adapted for use adjacent a supply reel for a bolt of doubled fabric, the singling and spreading element consisting of a single length of round metal rod stock shaped to form a pair of upwardly projecting arms converging and integrally united in a somewhat rounded apiced portion, the exterior surface of the singling and spreading element being smoothed to minimize resistance and obviate snagging effects on the cloth as same is moved thereover, the lower ends of the singling structure being of substantially vertical trend, and a vertical socket at each side of the carriage, each socket located for detachably receiving one of said vertical end portions and supporting the singling and spreading element.

5. In a device for singling and spreading doubled fabrics from a supply bolt thereof, a carriage, a table for cutting or the like, along which the carriage is operable, a vertical bolt reel intermediate the sides of the carriage, an inverted V-shaped singling element bridging and projecting upwardly from opposite sides of the carriage, and characterized by a pair of substantially right-angularly related arms connected by a rounded upper portion located somewhat below the top of the bolt reel, and so adapted substantially to half open the doubled fabrics as it is withdrawn from the reel, means on the carriage spaced below the singling element for directing the singled cloth to a horizontal plane on the table, and means providing for a manually adjustable resistance or braking effect on the bolt reel, whereby to prevent overrunning thereof as the fabric is moved from the reel over the singling element and onto the table.

6. In a cloth singling and spreading machine, a rolling frame, an elongate horizontal table over which the rolling frame is adapted to operate for cloth spreading purposes, a single track at one side of the table, a reel carried by the frame for holding a supply bolt of cloth to be singled and spread, a wishbone structure converging above and arranged transversely of the frame, means enabling a variation in the cross frame members of the frame for adjustment of frame width, the wishbone structure being of sufficient flexibility to adjust itself to the different adjusted widths of rolling frame.

7. In combination, an elongate cloth possessing table, a carriage operable along the table, a vertical supply reel on the carriage for a bolt of cloth to be singled and spread on the table, a pair of horizontal cloth-spreading rollers on the carriage, means for adjusting the effective lengths of the rollers, and a cloth-dividing and singling structure between the supply reel and the rollers, the last said structure being self-adjusted responsively to variation in effective lengths of the spreading rollers while maintaining a substantially constant relation to the doubled fabric as same is drawn from a bolt on the supply reel.

8. In combination, an elongate cloth-receiving

table, a single track extending along one edge of said table, a carriage operable along the table and directed by said track, a supply reel for doubled fabric, mounted on the carriage, a wishbone mounted substantially transversely of the carriage and adapted to single or divide doubled layers of cloth as drawn from the reel, a plurality of horizontal spreading and flattening rollers mounted on the carriage, means associated with the frame members of the carriage to enable a variation thereof to accommodate different widths of cloth to be spread, the wishbone and the spreading rollers being self-accommodating and self-adjusting to the carriage irrespective of variation in width thereof, and while preserving a substantially constant relation to the layers of cloth drawn from the supply reel over the wishbone and between the rollers for deposit on the table.

20 9. In a cloth-spreading machine for singling and spreading doubled cloth fabrics, a reel for a supply bolt of doubled cloth, dividing means on the carriage beyond the reel, a plurality of spreading rollers engaging opposite sides of the cloth, and means for lifting the rollers as successive layers of cloth are deposited on the table, said lifting means including a vertically swingable arm on each side of the carriage, a cable supporting each of said arms, a reel for each cable and means for retaining the reels in adjusted position whereby to secure the spreading rollers at various predetermined heights above the table.

30 10. In a device for singling and spreading doubled layers of fabric from a supply bolt thereof, a carriage, an elongate table for receiving the singled layers of cloth and over which the carriage is movable, a vertical reel on the carriage, for supporting a supply bolt of cloth, an inverted V-shaped spreader serving as a singling device 35 beyond the reel, the sides of which are so related that as the cloth is drawn thereover, the device serves to half-open the adjacent doubled layer, two sets of flattening rollers horizontally disposed on the carriage, one set being substantially 40 above the other set of rollers and so arranged that the cloth is adapted to be passed under one and over another of the rollers of the upper set, just after leaving the singling device, in a manner to complete singling and eliminate fold 45 marks, the rollers being so arranged that the cloth is drawn thence downwardly between the rollers of the second set.

50 11. In a device for singling and spreading doubled layers of a cloth or fabric from a supply bolt thereof, a carriage, an elongate table for receiving the singled layers of cloth and over which the carriage is movable, a vertical reel for supporting a supply bolt of cloth and mounted on the carriage, an inverted V-shaped singler and spreader close to, but beyond the reel in the direction of cloth movement therefrom, the spreader being characterized by a pair of downwardly divergent arms, each of a length generally approximating the width of one of the singled cloth layers, the arms being angularly related to effect a right angular divergence of the layers of cloth, two sets of flattening rollers horizontally disposed on the carriage, one set being substantially 55 above the other set of rollers and so arranged that the cloth is adapted to be passed downwardly, after leaving the singler and spreader, under one and over another of the rollers of the upper set, to flatten the initially doubled cloth and relieve it of fold lines, thence downwardly between the rollers of the second set, and means for ad-

justing the lower set of rollers to various heights from the table, each of the rollers of the lower set being provided with cloth guiding projections at the opposite ends.

12. In a cloth-spreading carriage adapted to coat with a table or like surface for the deposit of single layers of an initially double-bolted fabric, a vertically disposed rotatable supply reel on the carriage, a wishbone type singler mounted in a generally transverse position on the carriage 10 and with its apex portion at about the height of

issuance of the fabric fold from a supply bolt on the reel, means enabling an adjustment in width of the frame structure of the carriage by effecting different spacings of the carriage side members, the wishbone structure being so formed as to accommodate itself to different widths of carriage while substantially maintaining the position of its apex portion with respect to the supply bolt.

THEODORE J. GUNDLACH.
